UNITED STATES PATENT OFFICE.

CHARLES P. TOLMAN, OF NEW YORK, N. Y., ASSIGNOR, BY MESNE ASSIGNMENTS, TO ROTENG ENGINEERING CORPORATION, OF NEW YORK, N. Y., A CORPORATION OF NEW YORK.

AIR-COMPRESSOR.

No. 888,553.

Specification of Letters Patent.

Patented May 26, 1908.

Application filed March 21, 1906. Serial No. 307,182.

To all whom it may concern:

Be it known that I, CHARLES P. TOLMAN, a citizen of the United States, residing at New York city, in the State of New York, have invented a new and useful Air-Compressor, of which the following is a specification.

My invention relates to improvements in air compressors and engines, or motors, of the rotary type in which radially disposed cylinders securely attached to, or an integral part of a hub, are mounted to turn on a spindle or bearing, said cylinders being fitted with pistons which reciprocate therein and which are movably mounted to turn about an axis eccentric with reference to the axis of revolution of the cylinders.

The object of my invention is to provide a simple and compact compressor or motor which shall be of the highest possible efficiency.

My invention consists of the novel construction, arrangement and combination of the various devices and parts, as hereinafter more particularly described and specified in the claims.

In the drawings I show a construction by which the invention may be carried out, in which

Figure 1 is a vertical section of the device taken longitudinally through the axis of the main bearing; Fig. 2 a side view of the combination bearing; Fig. 3, a horizontal longitudinal section of the combination bearing; Fig. 4, an end view of said bearing; Figs. 5 and 6, sectional views of the same on lines *a*—*b* and *c*—*d* respectively of Fig. 3.

Similar numerals refer to similar parts throughout the drawings.

Referring to the drawings, a frame or support 29, provided with an oil reservoir 19, supports a combination bearing shown in Fig. 2, which consists of an eccentric bearing 2 and a main bearing 9, the interior of which is hollow and divided by a partition 27 into two compartments 14 and 15, one for intake and the other for discharge of fluid. A hub 20, which carries a plurality of cylinders 1, is revolvably mounted on said main bearing 9, said cylinders being provided or fitted with

roller bearings 13, which protrude into annular grooves in cover plate 4 and case 3, by which said pistons are supported in said cylinders. The outer extremities of the pistons are preferably provided with flat surfaces on both sides which fit into annular recesses provided in cover plate 4 and case 3, the object of such a construction being to prevent accidental rotation of the pistons in their respective cylinders, which rotation would interfere with the proper operation of rollers 13. Case 3 is revolvably mounted on eccentric bearing 2, and is provided with oil drainage holes 11 to allow escape of excess oil from said case into the frame or support 29. An oil guard flange 10, attached to or an integral part of said case 3, operates within a receiving flange 21, which receiving flange catches any excess oil delivered to it by centrifugal force from oil guard flange 10, and permits the same to drain into oil reservoir 19. The inner end of each cylinder is provided with a suitable port 22, which leads through hub 20 into main bearing 9, and which is capable of communication with suitable ports 14' and 15' in the wall of main bearing 9 which leads respectively into compartments 14 and 15 of the combination bearing.

Hub 20 is provided, at each end, with a recess into which is placed a suitable backing 6 (shown in the drawing as a metallic ring) and suitable backing followers 7, which followers are attached to the hub in any suitable manner. One end of said hub is extended sufficiently to permit the attachment thereto of any desirable drive shaft or shaft to be driven, as by coupling 18; and, if desirable, said extension may be provided with a pulley 24, suitably attached to the hub, or an integral part thereof, for driving the device as a compressor, or for transmitting power when it is used as a motor. A retaining ring or collar 23, suitably attached to the end of main bearing 9, serves to restrain hub 20 in place.

A groove 26 in one end of the combination bearing receives a supply of lubricant from a suitable connection 25 in case 29. Ducts 16 and 17, shown in Fig. 3, convey a portion of said supply of lubricant to the intake passage 14 of the valve within main bearing 9, the

balance of said supply being led by similar ducts, or by grooves, to the other surfaces requiring lubrication.

It is apparent that when the device is used as a compressor, compartment 14 in the combination bearing is preferably used for intake and compartment 15 for exhaust of fluid; and that when the device is used as a motor, the motive agent being a fluid under pressure, or when it is used as a vacuum pump, compartment 14 is the exhaust chamber and compartment 15 is the intake chamber or compartment. Briefly, it will be seen that by reason of its being more readily attached, compartment 15 is preferably the one to be used for connection to that part of a system where a fluid tight joint is desirable.

With the cylinders, pistons and case in the mechanical relation above described the case is free to take up such rotation on eccentric bearing 2 as it will; but it is preferable to provide means whereby the case will be caused to revolve at the same average speed as the cylinders. This may be accomplished in many ways, one such means, for example, being by substituting for one of the rollers 13 a bin 28 which is secured to the case 3 and the piston pivotally mounted thereon. The remaining pistons are mounted as previously described in such manner as to provide for the relative motion of the rollers and the case during each revolution. This variation, unavoidably takes place since the case bearing 2 and the cylinder hub bearing 9 are eccentric one to the other.

Since case 3 revolves about a bearing eccentric to the axis of revolution of cylinder hub 20, the pistons will complete an in and out stroke for each revolution of the cylinder hub. With the apparatus operating as a compressor and the moving parts starting from the position shown in Fig. 1 and revolving clockwise—when the view is taken from the coupling end, it will be seen that the upper cylinder, during its first half revolution, is in communication, through its port 22 and port 14', with the intake passage or compartment 14 in the combination bearing, and that its piston completes its outward or intake stroke during this half revolution. The continued rotation of the mechanism to complete a revolution brings about the inward stroke of the piston, which stroke compresses the fluid agent within the cylinder, and when the cylinder port 22 comes into communication with exhaust passage 15 through port 15', the fluid under pressure in said cylinder is expelled into said exhaust cavity and from thence to any connected apparatus.

With the apparatus operating as a motor, the motive agent being supplied to the apparatus from a source of supply connected to compartment 15, said agent being a fluid under pressure, it is apparent that said motive

agent will pass from compartment 15 through its port 15' and through port 22 of the cylinder which happens to be in the proper angular position to receive said agent. The action of this agent on the piston in said cylinder forces the piston outward, thereby causing rotation of the apparatus. As this rotation continues port 22 finally overtravels port 15' and the supply of motive agent is thereby cut off from this cylinder; the ports of the succeeding cylinders are brought into communication with said port 15', and the further rotation of the apparatus brings port 22 of the first cylinder into communication with port 14' of passage 14, through which passage the motive agent is discharged or exhausted from said cylinder, each succeeding cylinder being discharged in a similar manner as the revolution of the apparatus is continued.

I do not wish to be confined to the precise arrangement or combination of parts here described or shown as the same are capable of modification without departing from the principles of my invention.

What I claim is:

1. A rotary compressor comprising a stationary frame, a bearing carried by said frame, and supporting a hub, radially disposed cylinders mounted on and secured to the hub, an inclosing casing revolvably supported on an eccentric portion of said bearing, and pistons in said cylinders, said pistons being suspended in their respective cylinders by means of rollers which are operative in annular grooves formed in the sides of said casing.

2. A rotary compressor comprising a bearing carried by a stationary frame and having thereon an eccentric portion, a hub supported on said bearing and having mounted thereon radially disposed cylinders; an inclosing casing revolvably mounted on the eccentric portion of said bearing, and having an annular groove in each side of the casing concentric with said eccentric portion of said bearing and pistons suspended in said cylinders from rollers which are operative in said annular grooves, said pistons having their outer extremities provided with flat surfaces, which engage an annular recess in said casing.

3. In a device of the class described the combination of a frame, a bearing carried by the frame and having means therein for inlet and outlet of fluid, a hub rotatably supported on said bearing and having a recess at each end, packing in each recess and packing followers for retaining said packing in said recesses, a plurality of radially disposed cylinders mounted on and secured to the hub, an inclosing casing rotatably mounted on an eccentric portion of said bearing, pistons movably suspended in the cylinders from annular grooves in said casing, and a lubricant

supply system for all bearing surfaces comprising a common source of supply in the frame, a receiving groove in the bearing in communication with said source of supply 5 and ducts and grooves in said bearing leading from said receiving groove to all bearing surfaces.

In testimony whereof I affix my signature in the presence of two witnesses.

CHARLES P. TOLMAN.
